(57) **CLAIM**

The ornamental design for a test device comprising a pipette holder, as shown and described.

DESCRIPTION

FIG. 1 is a top perspective view of a test device comprising a pipette holder, with a pipette in place;

FIG. 2 is a first end view thereof;

FIG. 3 is a second end view thereof;

FIG. 4 is a first side view thereof;

FIG. 5 is a second side view thereof;

FIG. 6 is a top view thereof;

FIG. 7 is a bottom view thereof; and,

FIG. 8 is a second perspective view thereof.

The broken lines in the figures depict portions of the test device comprising a pipette holder that form no part of the claimed design. The dot-dashed broken lines depict the boundaries of the claim and form no part thereof.

1 Claim, 8 Drawing Sheets
